UNITED STATES PATENT OFFICE.

JOHN H. BURKHOLDER, OF ASHLAND, OHIO.

PUMP.

No. 848,629.

Specification of Letters Patent.

Patented April 2, 1907.

Application filed July 12, 1906. Serial No. 325,903.

To all whom it may concern:

Be it known that I, JOHN H. BURKHOLDER, a citizen of the United States, residing at Ashland, in the county of Ashland and State of Ohio, have invented new and useful Improvements in Pumps, of which the following is a specification.

This invention relates to improvements in pumps, and more particularly to a compound air-pump.

The object of the invention is to provide a device of this character which will be of simple, compact, and durable construction and very powerful in operation.

15 The above and other objects, which will appear as the nature of the invention is better understood, are accomplished by the construction illustrated in the accompanying drawings, in which—

20 Figure 1 is a side elevation of the improved pump. Fig. 2 is a vertical section of the same, and Fig. 3 is a detail sectional view through the pistons.

In the present embodiment of the invention I provide two cylinders 1 and 2, the former of which is of greater diameter than the latter. These cylinders have their lower ends screwed or otherwise secured in a suitable base 3, here shown in the form of a loop adapted to receive the foot of the operator. In an extended portion of the base 3 is formed a passage 4, having one end in communication with the smaller cylinder 2. In the opposite end of the passage 4 is screwed a 25 nipple 5, adapted to receive a flexible tube or hose 6, which carries at its free end the usual valve connection 7. The upper end of the cylinder 1 is closed by a screw-cap 8, and the upper end of the cylinder 2 is closed by a screw-cap 9, in which latter is provided a packing-gland 10 of well-known form.

In connection with the cylinders 1 and 2 I employ a hollow or tubular operating V-shaped element 11, which has two arms 12 and 13, adapted to reciprocate in said cylinders and to carry pistons 14 and 15. These pistons 14 and 15 are in the form of cup-shaped disks of leather or the like secured between metal plates or disks by means of nuts, as 35 clearly shown in Figs. 2 and 3 of the drawings. The tube or hollow rod 12 is adapted to slide freely through the cap 8 and to have in its lower end, which opens beneath the piston 14, a check-valve 16 of any suitable form and

construction which will permit of the inlet of 55 air into said tube 12. The tube or hollow rod 13 is adapted to slide through the cap 9 and its packing 10 and has its lower end closed, as shown at 17. In the lower end of this tube 13 above its piston 15 is formed an 60 outlet opening or aperture 18. The upper ends of the tubes 12 and 13 are screwed or otherwise secured in a hollow or tubular connecting-arch 19, which permits of free passage of air from the tube 12 to the tube 13. 65 The arch or yoke 19 is preferably in the form of a casting and has at its top an upwardly-projecting screw-threaded stud 20, on which is rotatably mounted a cross-bar or handle 21.

The operation of the pump is as follows: 70 Upon the upstroke of the operating frame or element 11 the air in the cylinder 1 above the piston 14 will pass beneath the latter, and at the same time the air in the cylinder 2 above the piston 15 will pass beneath said 75 piston, the air being forced between the side walls of the cylinders 1 and 2 and the flexible depending flanges of the cup-shaped disks of the pistons. Upon the downstroke of the element 11 air will be drawn in the cylinder 1 80 through apertures, as 8, in the cap 8, above the piston 14, and air in said cylinder beneath said piston will be compressed and forced through the check-valve 16 into the arm or tube 12 and is forced upward there- 85 through and through the arch 19 into the arm or tube 13, from which it escapes through the opening 18 and enters the cylinder 2, while the air in the cylinder 2 beneath the piston 15 is forced out through the pas- 90 sage 4 and discharged from the hose or other connection 6. It will be observed that the construction of the device is exceedingly simple and compact, so that the pump may be manufactured at a comparatively small cost 95 and will be very durable in use. It will also be seen that it is very powerful and at the same time convenient and easy to operate.

While I have shown and described the preferred embodiment of the invention, it will be understood that I do not wish to be limited to the precise construction herein set forth, since various changes in the form, proportion, and minor details of construction may be made without departing from the spirit or 100 sacrificing any of the advantages of the invention as defined by the appending claims.

Having described my invention, what I

claim as new, and desire to secure by Letters Patent, is:

1. In a pump the combination of a pair of cylinders arranged parallel to each other, a tubular U-shaped hollow element having its legs operating in said cylinders and provided with pistons, said tubular legs having means for affording communication between said cylinders.
  2. In a pump, cylinders, and a tubular operating element having piston-carrying arms, one of said arms having its inner end opening upon one side of its piston and the other of said arms having its inner end opening upon the opposite side of its piston.
  3. In a pump, cylinders, a tubular operating element having hollow arms, pistons upon said arms and a valve in one of said arms, the other of said arms having an aperture adjacent to its closed end.
  4. In a pump, cylinders, a tubular operating element having hollow arms to reciprocate in said cylinders, one of said cylinders having an outlet connection, pistons upon said arms, the arm in the last-mentioned cylinder having its inner end closed and an aperture adjacent to said closed end and above the piston on said arm, and a check-valve in the other of said arms.
  5. In a pump, large and small cylinders, said small cylinder having an outlet, a tubular operating element having hollow arms in communication with each other, pistons upon said arms in said cylinders, the arm in said small cylinder having a closed inner end and
- an aperture above its piston, and a check-valve in the open end of the arm in said large cylinder.
6. In a pump, a base, cylinders projecting therefrom, an outlet connection for said base in one of said cylinders, closures for the outer ends of said cylinders, a tubular operating element comprising hollow arms adapted to reciprocate in said closures and a hollow arch connecting said arms, valves upon said arms within said cylinders, one of said arms having its inner end closed and formed with an aperture above its valve and a check-valve in the open inner end of the other of said arms.
  7. In a pump, a base, cylinders projecting therefrom, an outlet connection in said base for one of said cylinders, closures for the outer ends of said cylinders, a tubular operating element comprising hollow arms adapted to reciprocate in said closures and a hollow arch connecting said arms, valves upon said arms within said cylinders, one of said arms having its inner end closed and formed with an aperture above its valve, a check-valve in the open inner end of the other of said arms, a foot-loop upon said base, and a handle upon the connecting-arch of said operating element.

In testimony whereof I have hereunto set my hand in the presence of two subscribing witnesses.

JOHN H. BURKHOLDER.
